(57) **CLAIM**

The ornamental design for a golf club head, as shown and described.

DESCRIPTION

FIG. 1 is a top perspective view of a golf club head according to a first embodiment;
FIG. 2 is a front and bottom perspective view of the golf club head of FIG. 1;
FIG. 3 is a rear and bottom perspective view of the golf club head of FIG. 1;
FIG. 4 is a left side and bottom perspective view of the golf club head of FIG. 1;
FIG. 5 is a right side and bottom perspective view of the golf club head of FIG. 1;
FIG. 6 is a front elevational view of the golf club head of FIG. 1;
FIG. 7 is a rear elevational view of the golf club head of FIG. 1;
FIG. 8 is a top view of the golf club head of FIG. 1;
FIG. 9 is a bottom view of the golf club head of FIG. 1;
FIG. 10 is a left side view of the golf club head of FIG. 1;
FIG. 11 is a right side view of the golf club head of FIG. 1;
FIG. 12 is a top perspective view of a golf club head according to a second embodiment;
FIG. 13 is a front and bottom perspective view of the golf club head of FIG. 9;
FIG. 14 is a rear and bottom perspective view of the golf club head of FIG. 9;
FIG. 15 is a left side and bottom perspective view of the golf club head of FIG. 9;
FIG. 16 is a right side and bottom perspective view of the golf club head of FIG. 9;
FIG. 17 is a front elevational view of the golf club head of FIG. 9;
FIG. 18 is a rear elevational view of the golf club head of FIG. 9;
FIG. 19 is a top view of the golf club head of FIG. 9;
FIG. 20 is a bottom view of the golf club head of FIG. 9;
FIG. 21 is a left side view of the golf club head of FIG. 9;
and,
FIG. 22 is a right side view of the golf club head of FIG. 9. The broken lines shown on the drawings form no part of the claimed design.
